UNITED STATES PATENT OFFICE

115,162

DESIGN FOR A JAR

Frasier Smith, Wheeling, W. Va., assignor to
Seeman Brothers, New York, N. Y., a corpora-
tion of New York

Application March 13, 1939, Serial No. 83,556

Term of patent 7 years

To whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing forming part thereof.

Figure 1 is a front view of the jar showing my new design.

Figure 2 is a side view thereof; and

Figure 3 is a plan view.

I claim:

The ornamental design for a jar, as shown.

FRASIER SMITH.
